Primary Examiner — Kevin K Rudzinski*Assistant Examiner* — Clare Ann Gannon(74) *Attorney, Agent, or Firm* — Faegre Drinker Biddle & Reath LLP(57) **CLAIM**

The ornamental design for a shoe bottom cleansing apparatus, as shown and described.

DESCRIPTION

FIG. 1 is a perspective view of a shoe bottom cleansing apparatus showing my new design.

FIG. 2 is a top view thereof.

FIG. 3 is a bottom view thereof.

FIG. 4 is a right side view thereof.

FIG. 5 is a left side view thereof.

FIG. 6 is a front view thereof.

FIG. 7 is a rear view thereof; and,

FIG. 8 is a perspective view thereof in use with a shoe. The elements shown in broken lines show environmental structures that form no part of the claimed design.
